Primary Examiner — R. Johnson

(57) **CLAIM**

The ornamental design for an LED music device for dance mat, as shown and described.

DESCRIPTION

FIG. 1 is a front perspective view of an LED music device for dance mat, showing my new design;

FIG. 2 is a rear perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a front perspective view thereof, the LED music device shown as used with a dance mat; and,

FIG. 10 is a rear perspective view thereof.

The broken lines illustrates portions of the LED music device and a dance mat that form no part of the claimed design.

1 Claim, 10 Drawing Sheets
